(57) **CLAIM**

The ornamental design for a beverage can seal, as shown and described above.

DESCRIPTION

FIG. 1 is a front perspective view of a beverage can seal of the present invention;

FIG. 2 is a front perspective view of FIG. 1, showing the beverage can seal in use with an exemplary beverage can; FIG. 3 is a front elevational view of the beverage can seal of FIG. 2;

FIG. 4 is a rear elevational view of the beverage can seal of FIG. 2;

FIG. 5 is a right side view of the beverage can seal of FIG. 2;

FIG. 6 is a left side view of the beverage can seal of FIG. 2; and,

FIG. 7 is a top plan view of the beverage can seal of FIG. 2.

The broken lines are shown for the purpose of illustrating environmental subject matter of an exemplary beverage can and form no part of the claimed design.

1 Claim, 5 Drawing Sheets
